(57) **CLAIM**

The ornamental design for a vehicle upper body, as shown and described.

DESCRIPTION

FIG. 1 is a front elevational view of vehicle upper body showing my new design;

FIG. 2 is a rear elevational view thereof;

FIG. 3 is a plan elevational view thereof;

FIG. 4 is a three-quarter, bottom rear perspective view thereof;

FIG. 5 is a three-quarter, bottom front perspective view thereof;

FIG. 6 is a left side perspective view thereof;

FIG. 7 is a right side elevational view thereof;

FIG. 8 is a three-quarter, left front perspective view thereof; and,

FIG. 9 is a three-quarter, left rear perspective view thereof. The broken lines shown in throughout the drawing are shown for illustrative purposes and form no part of the claimed design.
